HYDRAULIC REMOTE CONTROL DEVICE

René Lucien, Farnham Common, England, assignor to Societe D'Inventions Aeronautiques et Mecaniques S. I. A. M., Fribourg, Switzerland, a corporation of Switzerland

Application June 19, 1944, Serial No. 540,990
In Great Britain March 24, 1943

2 Claims. (Cl. 60—51)

1

This invention comprises improvements in or relating to hydraulic remote control devices. It is an object of the invention to provide means for the remote control of hydraulic apparatus such as jacks, for example in aircraft, which combines the advantages of centralised supply and control with rapid operation and freedom from risk of breakdown on interruption of supply.

On aircraft, especially on large aircraft, or on installations of hydraulic apparatus in other connections where the parts to be controlled are remote from the point of control and from the pressure source, if promptitude and reliability of operation are required it is necessary to provide large-diameter piping which extends from the pressure-source to the apparatus in order that the flow of liquid may be prompt and free. Furthermore it is ordinarily necessary to have the source of supply of high-pressure fluid located close to the point of control. The result is that the pipe-work is heavy. Moreover its diameter and length makes it vulnerable and damage at any place in the pipe-system is likely to throw the whole installation out of order. Finally, the pump ordinarily employed as the source of supply, must have an output fast enough to operate the apparatus at the desired speed.

It has been proposed to control hydraulic jacks on an aircraft from a central control station by control means having electrical transmission and to have the hydraulic installation located in close conjunction with the jacks. This reduces weight and vulnerability but involves complication by introduction of the electrical apparatus.

In order to ensure reliable extension of an under-carriage irrespective of damage to pipe-work it has also been proposed in prior United States patent specification No. 2,001,620 to provide for movement in the direction of extension being effected by pressure supplied by an accumulator located close to the jack so that only retraction needs to be effected by liquid supplied from the pressure-source. Certain risks due to the possibility of damage to the intermediate piping were thus obviated and the quantity of pipe-work was reduced, but still the flow of the fluid had to take place in the full volume necessary for operation, through a length of piping extending the whole way between the pressure-source, the point of control and the jack and the capacity of the pump and size and weight of the piping necessary had to be designed accordingly.

According to the present invention a hydraulic system wherein the apparatus to be operated is located at a distance from a point of control and

2

from a pressure-source, comprises, in combination, an accumulator located close to the apparatus (jack or other device) to be operated, operating valve-means and connections between the accumulator and said apparatus to enable the accumulator when charged to operate the jack under control of said operating valve-means, hydraulic remote-control actuating means for the operating valve-means, including connections to the point of control, and a pressure-line from the pressure-source to the accumulator for charging the same.

In this way only the short connections between the accumulator and jack require to be of large size, the pressure-line and the connections to the point of control may be small and light. The pressure-source, such as a pump, may be of small capacity inasmuch as its function is to charge the accumulators and not directly to operate the jacks or the like.

Where, as is usual, the apparatus to be operated comprises several distinct devices, a plurality of accumulators may be provided therefor with separate operating valve-means for each device all connected by hydraulic remote-control means to the control point and the pressure-source may be connected to the accumulators by a branched pressure-line which serves them in common.

30 Preferably when the hydraulic devices include a jack a hydraulically-controlled locking-device may be provided for one end of the movement (or both ends of the movement) of the jack and the operating valve-means include a connection 35 to the locking device to unlock it when the valve-means are operated to apply pressure to the jack to move it. In this way the apparatus in the case of any failure in the pipe-work may be caused by the locking device to remain in the position in 40 which it has already been set and may also not be disturbed in the event of any failure in the supply pump.

It will be appreciated that the small capacity 45 required of the control connections permits the use of very light pipes and this results not only in a saving of weight, which is important in the case of aircraft, but also in a reduction of the risk of damage in combat, which is important 50 in the case of military services. Furthermore such piping is much more easily installed.

The following is a description, by way of example, of one installation in accordance with the invention:

55 The accompanying drawing is a diagrammatic

representation of the parts of the system and of the interconnecting pipe-work.

The installation comprises a number of hydraulic jacks on an aircraft (of which one only is shown at 11) connected respectively to the undercarriage framework for retracting the same, to bomb doors, to landing flaps and the like (not shown in the drawing) as may be desired. Closely associated with each jack, or with a group of jacks where several jacks are located close together, is a hydraulic accumulator 12 of sufficient capacity to operate the jack or jacks at least once in each direction. The accumulators are connected through non-return valves 13 by small-bore pipe-work 14, 15 with a central supply pump 16 located in a position where it can readily be driven by one of the engines of the aircraft. This pump may be of small capacity and will be required to run on load for a longer proportion of the working period than is usual with hydraulic pumps on aircraft, which is beneficial from the point of view of the pump. The function of the pump is to charge the accumulators, which may be done slowly. It will be observed that the pipe 15 is branched at 14 to the accumulator 12 and other branches will be provided to the other accumulators. The accumulators are connected each by a short pipe 17 and 21 of large bore to an operating valve (in two parts 18, 19) for each jack and the operating-valves by similar pipes 20 and 21 to the jacks. Thus when the operating-valves are operated the jack is operated rapidly, irrespective of the supply capacity of the pump.

Each end of the jack cylinder 11 is connected by the pipes 20, 21 to a supply compartment 22 in the operating-valve casing. Through the supply compartment 22 there passes the hollow stem 23 of a lift-valve 24 the exterior of which passes through the walls of the compartment with a fluid-tight fit. Outside the compartment is an admission chamber 25 which is spanned by a diaphragm 26 containing a seating for the head of the lift-valve and one of the supply connections 27 from the accumulator 12 enters the admission chamber. The hollow stem 23 has a port 28 connecting the interior of the stem with the admission chamber 25 below the diaphragm 26 so that if the valve 24 is lifted from its seating the pressure fluid from the accumulator will enter the stem through the port. Another port 29 in the stem connects the interior of the stem with the supply compartment 22 which is connected to the jack by pipe 21. Thus when the lift-valve 24 of either valve 18 or 19 is raised from its seating, the end of the jack 11 which is connected to the compartment will receive fluid under pressure from the accumulator. The interior of valve 19, of which only the exterior is shown, is similar to that of valve 18.

As above stated, the stem 23 of the lift-valve passes right through the supply compartment 22 and out through the wall thereof on the opposite side from the head of the valve. The end of the stem is open and carries a seating 30. Beyond the compartment the end of the stem projects into an exhaust cylinder 31 which is connected by a port 32 to a drain pipe 33. In the cylinder 31 works a tappet 34 which can be moved so that it engages the seating 30 around the end of the stem 23 and thereby seals the interior of the valve stem from the drain, while further movement of the piston or tappet would lift the valve 24 from its seating. It will be appreciated therefore that movement of the actuating tappet 34 in one direction lifts the valve and applies pressure to the

jack and in the other direction allows the valve to seat and connects the jack through the supply compartment 22 and the interior of the valve stem 23 to the drain pipe 33.

5 Beyond the exhaust cylinder 31, and axially in line therewith, is a larger actuating or motor cylinder 35 containing a relay piston 36. This piston may be broadly designated a valve-actuating motor. The relay piston 36 has a stem 37 which is capable of engaging the tappet 34 in the exhaust cylinder but is urged away therefrom by a spring 38. Behind the relay piston the operating cylinder is provided with a connection to a fine-bore control-pipe 39 (or 40 as the case may be) and when pressure is applied in the operating cylinder 35 by fluid supplied through the control-pipe the stem of the piston therein is urged against its spring 38 into contact with the piston or tappet 34 in the exhaust cylinder 31 and thereby closes the piston against the lift-valve, and if the movement is continued lifts the lift-valve from its seating.

25 The two control-pipes 39, 40 which open into the two actuating cylinders 35 are connected to a control-box in two parts 41, 42 located in a central point of control on the aircraft where it can readily be controlled by the pilot or other personnel. Each control-box comprises a lever 43, which lever operates control lift-valves 44, 45. 30 The valves 44 admit hydraulic fluid under pressure from a compartment 46 to compartment 47 of the box, and thence to one of the control-pipes 39 when one lever 43 is moved in one direction and the other control-pipe 40 when the other lever 43 is moved in the other direction. The levers 43 are linked by spindle 48 to move in unison and controlled by handle 49. The fluid under pressure is supplied to the control-box from the aforesaid central pump 16 by pipe 50 and only a very small quantity of fluid is necessary to operate the relay pistons and open the lift-valves of each jack. (It will be understood the cylinders 35, 31, 18 and 19 and associated parts are not to scale and in practice are much 45 smaller in proportion to the size of the other parts than is possible to show on the drawing.)

40 The valves 45 when opened connect the compartments 47 to compartments 51 and the compartments 51 are connected to a drain pipe 52. 50 The valve 45 in each box is opened by lever 43 when valve 44 is closed. The boxes 41, 42 are reversed in relation to one another so that when pipe 39 is under pressure pipe 40 is open to drain, and vice versa.

55 A similar pair of control-boxes 41, 42 and handle 49 is provided at the central station for each jack in the system and thus by a system of very light pipe-work the connections of the jacks to their respective accumulators can be controlled 60 as desired and the jacks operated in either direction without necessitating the whole of the operating fluid flowing all the way to the jacks from the pump 16 during the period of operation.

Furthermore, some of the jacks, particularly 65 the under-carriage jacks, may be provided with hydraulically-operated bolts 53, 54 or their equivalent for locking them in one or other extreme of movement. These bolts are slidably mounted in cylinders 55, 56 which contain bolt-withdrawing 70 pistons and return springs. The cylinders which contain the bolt-withdrawing pistons are connected by short pipes 57, 58 to the actuating cylinders 35 which contain the relay pistons 36. The connections for this purpose extend to the 75 centre of that end of the actuating cylinders to

which the control pipes 39, 48 are connected and the ports 59 by which the connections from the hydraulic locking bolts 53, 54 enter the relay cylinders are surrounded by seatings 60 which are arranged to be engaged by co-operating seatings on the relay pistons 36 when the latter are fully retracted under the influence of their springs 38 to allow the lift valves 24 to close.

In operation, the first effect of admission of pressure to one of the actuating cylinders 35 is to move the relay piston 36 off the central seating 60 and to admit control fluid under pressure to one of the bolt-withdrawing cylinders 55 or 56, as the case may be, so that the jack is unlocked. After a short movement of the relay piston the rod 37 engages the tappet 34 in the exhaust cylinder 31 of the valve and opens the lift-valve 24 to cause the jack to move. The other lift-valve in the other operating-valve casing 18 or 19, as the case may be, is, of course, at this time open to drain pipe 33. The jacks are thus locked in either of their end positions until the relay pistons are operated, whereupon they are first unlocked and then have pressure applied to them to produce movement.

The drain pipe 33 is connected by a pipe 61 to a main return pipe 62, the pipe 61 being a branch from this so that only one return pipe 62 is needed to serve all the jacks in the system. The pipe 62 extends to a sump 63 to which also opens the pipe 62 and from which the pump 16 draws its supply. The pipe 62 should be of adequate diameter but is not under pressure and may be thin. Also only one such pipe is required and if ruptured it does not lead to any failure of operation, only loss of fluid.

The advantages of this system may be summarised as follows:

1st, rapidity of operation.

2nd, convenience of control.

3rd, the jacks are maintained in either of their extreme positions by direct pressure from the accumulator.

4th, in case of breakage of the control pipe-work the gear remains with its position unaltered.

5th, only short lengths of large diameter pipe are required, the long lengths of pipe-work being of small diameter and easily installed.

I claim:

1. A hydraulic operating system, comprising, in combination, a hydraulic jack; an accumulator adjacent said jack; hydraulic connections be-

tween said jack and said accumulator; operating valve means disposed in said connections to enable the accumulator, when charged, to operate the jack under the control of the operating valve means; hydraulic actuating valve means and a source of pressure; and piping independently connecting said accumulator and said actuating valve means with said pressure source, and said actuating valve means with said operating valve means; locking means for retaining said jack in a fixed position; and hydraulic fluid connections from said operating valve means to said locking means for actuating said locking means, said second-named connections being independent of the first-named hydraulic connections between said jack and said operating valve means; said second-named connections being supplied from said actuating valve means, but the transmission of operating pressure through said connections to said locking means being controlled by the movement of said operating valve means.

2. A hydraulic operating system, comprising, in combination, a hydraulic jack; and accumulator adjacent said jack; hydraulic connections between said jack and said accumulator, operating valve means disposed in said connections to enable the accumulator, when charged, to operate the jack under the control of the operating valve means; hydraulic actuating valve means and a source of pressure, and piping independently connecting said accumulator and said actuating valve means with said pressure source, and said actuating valve means with said operating valve means; said operating valve means comprising controlled passageways for pressure fluid passing from said accumulator to said jack, a valve element associated with said passageways, a valve-moving motor, and a motor chamber subject to fluid pressure from said actuating valve means; locking means for retaining said jack in a fixed position, a conduit leading from said motor chamber to said locking means, whereby said actuating valve means serves to actuate both the operating valve means and release said locking means, and means for covering the inlet of the conduit leading from said motor chamber to said locking means, when the operating valve means is idle, but which are moved to open said conduit upon the initial movement of said motor means as pressure fluid is admitted to said motor chamber from said actuating valve means.

RENE LUCIEN.
